UNITED STATES PATENT OFFICE.

DORR E. FELT, OF CHICAGO, ILLINOIS.

CALCULATING-MACHINE.

1,074,705.

Specification of Letters Patent.

Patented Oct. 7, 1913.

Application filed April 5, 1913. Serial No. 759,192.

To all whom it may concern:

Be it known that I, DORR E. FELT, a citizen of the United States, residing in Chicago, in the county of Cook and State 5 of Illinois, have invented a new and useful Improvement in Calculating-Machines, of which the following is a specification.

My invention relates to multiple-order keyboard calculating machines, including 10 such calculating machines as the well known comptometers set forth in, among others, my prior U. S. Patents Nos. 762,520 and 762,521 of June 29, 1904; No. 767,107 of Aug. 9, 1904; No. 960,528 of June 7, 1910; 15 No. 992,950 of May 23, 1911; No. 996,009 of June 20, 1911; Nos. 982,416 and 982,417 of Jan. 24, 1911; No. 1,003,723 of Sept. 19, 1911; and No. 1,028,344 of June 4, 1912; and to other machines with which it is 20 adapted to be combined in construction and operation.

The present invention relates more particularly to the canceling or zeroizing mechanism, and has for its object to prevent any 25 over-throw or further turning of the numeral wheels after they have arrived at zero, by reason of a violent operation of the canceling crank or handle and a rebound of the same at the end of its final canceling 30 and zeroizing stroke. And the invention has for further objects the effecting of all other improvements in structure or function that may be found to obtain in the mechanism hereinafter described or claimed.

35 In order to make the invention more clearly understood there are shown in the accompanying drawings means for carrying the same into practical effect, without limiting the improvements, in their useful 40 applications, to the particular constructions which, for the purpose of explanation, have been delineated.

In the said drawings—Figure 1 is a side view, of so much of a calculating machine 45 embodying the invention as is necessary for an understanding of the latter, the casting and base being removed. Fig. 1^a shows, in side elevation, the rear part of the machine omitted from Fig. 1. Fig. 2 is a 50 plan view showing the rebound-preventing device. Fig. 3 is a horizontal section of the same on line 3—3 of Fig. 1.

Following is a description of the particular calculating machine, including so much 55 of the accumulating and canceling mecha-

nism as is necessary to mention, to which the invention is in this instance applied.

Referring to the drawings, 1 indicates the vertical retaining plates constituting a part of the frame of the machine, and 2 60 the top plate thereof. The frame preferably comprises vertical side or retaining plates, such as are shown at 1, and similar intermediate plates one of which is, arranged in each of the spaces between the 65 numeral wheels 3. All of these vertical plates are secured to or mounted on a base (not shown) and are or may be rigidly connected by suitable cross bars or tie rods 4, and by the top plate 2. 70

The accumulator mechanism, including the numeral wheels, is caused to be actuated, in the calculating operation, by denominational series of finger keys 5 mounted to reciprocate vertically in guide apertures 75 or bearings in the top plate 2, and the lower end of each key stem is pressed upward by a lever and spring of known form (not shown) carried by lower frame parts 7.

For convenience I will recapitulate certain of the parts, and their functions, known in and by the prior patents above mentioned; but it is not necessary to an explanation of the present improvements to repeat all of the description and illustration 80 of said patents. The principal parts are the following: column actuators or segment levers 8 pivotally mounted at 9 on the frame 1, and yieldingly held up by accumulator

actuating springs 10; odd and even stop levers 11, 11', 12, 12' each of which may comprise two separate co-acting parts and which are pivoted to the rear and front of the frame at 13, 14; stop detents 15 carried by the lever parts 11', 12', to engage with 85 the coarse spaced teeth 17 on the column actuator and arrest the downward movement of the latter; accumulator pinions 18 mounted on the cross pivot accumulator shaft 19 and engaged and turned by the 100 column actuator segments; accumulator ratchets fixed to the pinions 18; lantern wheels having pawls pivoted thereon and arranged within the ratchets, whereby the ratchets turn backward freely but on their 105 forward movement rotate the lantern wheels by means of the said pawls; a back stop pawl, and a locking detent, for each lantern wheel, the locking detents being spring pressed away from the lantern wheels and 110

being pushed into engagement by roller studs 18' on the column actuator; intermediate gears on the intermediate pick up shaft 25, which are engaged and driven by 5 accumulator gears attached to the lantern wheels and which engage and drive the numeral wheel gears; carrying pinions attached to the accumulator gears and meshing with and driving carrying gears on the 10 cross pivot carrying shaft 29; carrying motor springs encircling the shaft 29 and connecting the carrying gears yieldably with rotary escapements on the shaft 29; two armed carrying cams fixed on the said escapements and given, by means of the said 15 carrying motor springs and escapements, a half revolution at each half revolution of the carrying gears or whole revolution of the carrying pinions; carrying levers each 20 of which is pivoted on the cross pivot shaft or rod 33 and is arranged in line with the lantern wheel in the next higher order of accumulator mechanism, said carrying levers being raised by the carrying cams at each 25 half revolution of the latter; carrying pawls pivoted, as are the locking detents, on the carrying levers and operating on the pins of the said next higher lantern wheel to move the latter and its accumulator mechanism one step at each carry; carry-detaining 30 latches to enable two keys in contiguous orders to be simultaneously depressed without losing a carry; cam-actuated three armed detents 36 for locking the carrying 35 levers; and canceling stops for positioning the accumulator mechanisms and numeral wheels in canceling, mounted on a rock bar 38.

The machine is of the duplex type; that is 40 to say, two keys side by side, in different orders, may be simultaneously depressed and each will have its proper and full effect in the accumulation. To this end the carrying mechanism is adapted to permit prime actuations of the accumulator mechanism in a 45 plurality of orders simultaneously. That such full effect of the depression of the key of lower order be attained it is necessary that any carrying, which may be due to take 50 place from the lower numeral wheel to the higher numeral wheel, shall not be lost by reason of the higher numeral wheel having such forward motion that the carrying mechanism may not affect it. The latch is 55 pivotally mounted on the cross rod 39 of the frame and extends over the carrying mechanism, resting at its inner or rear end on the stud pin 40 of the column actuator 8. The latch has a tooth which is adapted 60 to engage either (whichever may first encounter it) of the two projections on the rotary hub or sleeve of the carrying mechanism. When any key of the order to which a carry is to be made is struck the actuator 8 of that column and its pin 40 move

down, allowing the latch to drop where its tooth may engage a projection and arrest any rotation of the carrying devices which might at that time be ineffective. The carrying devices continue to be so held until 70 the column actuator 8 rises, and the key and numeral wheel of the higher order have completed or substantially completed their operation, whereupon the pin lifts the latch, and releases the carrying mechanism, and allows the latter to be actuated by its carrying spring to effect the proper carry which may be due to occur. The carrying mechanism of each column or order is provided with a set of the described parts. 75

43 is the latch releasing device, preferably a swinging release bar which releases the latches and connected carrying mechanisms and wound up carrying motor springs. It is formed with arms 44 pivoted to the frame 80 on the cross rod 39 and is arranged to engage the tail pieces of the latches at a point below the pivot cross rod 39 of the latches and force them backward to lift the latch teeth. 90

46 indicates links which pivotally connect with the arms 44 of the release bar at 47 above the pivot rod 39 and connect with the forward ends of release levers 49 at 50. These release levers, one at each side of the 95 machine, are pivoted to the frame at 51.

The canceling means, whereby the numeral wheels are reset at zero, comprises a canceling actuator, or cancellation controlling means, consisting in this instance of a 100 cross rock shaft 52, crank handle 53 and slotted cam 54. These parts operate on a canceling device comprising a segment lever 55 actuated by the slotted cam; a canceling pinion 56 on the canceling or intermediate 105 shaft 25; and means by which said shaft may rotate the intermediate gears when the shaft is in a certain position relative to the gears. The canceling means also comprises devices 110 effecting a one-space adding movement of the column actuators, consisting of a transverse bar 57 adapted to depress the column actuators one space and give a one-space adding movement to the accumulator mechanism, which bar is reciprocated vertically 115 by the slotted cam through the medium of arms 58, which carry the bar at their ends and are pivoted at 51 to the frame 1. All of these parts are or may be similar to those set forth in my said patents, and a showing 120 of most of them is unnecessary to an understanding of the invention herein claimed.

The canceling operation: For accuracy in bringing the numeral wheels from their various positions all to the "0" position, 125 those of the second and higher orders are first brought to the "8" position, and the units wheel is brought to the "9" position; then the cross bar 57 and the column actuators having been depressed one step, rise and 130

move all of the wheels one step, the wheels of higher order than units to the "9" position and the units wheel immediately after to the "0" position, the said movement of the units wheel being detained in a known manner by a slightly elongated tooth on its canceling stop, and causing the carrying mechanisms to operate, successively but practically instantaneously, across the machine from right to left to bring the said wheels of higher order to the "0" position and complete the canceling operation. There are the usual stop studs, one on each of the carrying pinions, which may engage the under side of the stops on the canceling stop levers or arms. The latter are affixed to the said transverse canceling stop rock bar 38 mounted to oscillate in the lower part of the frame. When the stops are rocked forward into the paths of the stop studs they are adapted to arrest the carrying pinions in such position that each numeral wheel of higher order than units is held positively in the "8" position, the units wheel stopping at the "9" position by reason of a little later (36 degrees) positioning of its stud on its pinions. The rock bar 38 is actuated by a cam and lever and toggle mechanism on the left side of the machine (not shown), which is set forth in the joint application of D. E. Felt and J. A. V. Turck filed Apl. 5 1913, Serial No. 759,193.

The means for preventing any possible rebound of the canceling actuator after it reaches the end of its final throw and has zeroized the machine, and any consequent forward turning of one or more of the numeral wheels, comprises a positive stop for said actuator. In the construction illustrated it is shown as consisting of a stop, tooth or hook 83 adapted to be moved momentarily into the path of a corresponding stop 84 on some part which is affixed to or connected with some part which is turned, reciprocated or moved by the canceling actuator. In this instance the stop 84 is formed with the slotted cam 54, and is arranged to be a little higher than the stop 83 at the instant when the canceling actuator is arrested at the end of its forward movement. The stop 83 is carried by an arm 85 pivoted at 86 to the frame of the machine, and is normally and when it is out of operation drawn back by a spring 87 against a fixed stop 88. Connected with the arm 85 is an arm 89 which extends across the upper part of the path of a pin 90 fixed on some part which turns with the canceling actuator, in this instance on the said slotted cam 54. The rearward rock of the canceling actuator is arrested by a stop arm 92 on the slotted cam, which encounters a fixed stop 93 on the frame. The forward rock of the said actuator is arrested by a part 94 on the slotted cam, which encounters the under side of the

said stop 93. The pin 90 is so positioned that it will, just before the end of the forward movement of the canceling actuator and slotted cam, engage the arm 89 and raise it slightly. If the forward movement of the canceling actuator is normal and usual, and without especial violence, there is no necessity for the action of the rebound stop, and the said engagement does not throw the stop 83 forward far enough to carry it into the path of the stop 84, the arm 85 being held back by the spring 87, as seen in Fig. 1. But if the pin 90 strikes the arm 89 with some violence the stop 83 is thrown forward under the stop 84, and on any attempted rebound of the canceling actuator the stop 83 engages and positively arrests the stop 84 and the canceling actuator. The stop 83 remains inactive during the first rearward movement of the canceling actuator and downward movement of the stop 84, and also during the reverse and final movement of said parts, except under the conditions and as above explained. To so proportion the parts that the stop 83 would be normally in the path of the stop 84 and would be withdrawn to inactive position as the stop 84 passes it at normal speed would be a variation of the construction illustrated and within the invention claimed. The main purpose of the rebound stop is to permit, as distinguished from deterring, interrupting or retarding, the most rapid operation and movement of the canceling handle, and to accelerate the machine in use, without allowing any possibility of misplacing the numeral wheels after they have been zeroized.

What I claim is—

1. In a calculating machine having multiple-order accumulator mechanism, including numeral wheels and carrying mechanisms, in combination a canceling device for restoring the accumulator mechanism to normal position or zero; and a positive stop acting when the canceling device has reached the end of its final throw to prevent the rebound of the canceling device and an improper positioning of the accumulator mechanism; substantially as specified.

2. In a calculating machine having multiple-order accumulator mechanism, including numeral wheels and carrying mechanisms, in combination a canceling device for restoring the accumulator mechanism to normal position or zero; and a positive stop movable into the path of a part of the canceling device at the end of its final movement and acting to prevent the rebound of the canceling device; substantially as specified.

3. In a calculating machine having multiple-order accumulator mechanism, including numeral wheels and carrying mechanisms, in combination a canceling device for restoring the accumulator mechanism to normal posi-

tion or zero; and a stop movable into the path of a part of the canceling device at the end of its final movement and acting to prevent the rebound of the canceling device, the canceling device having means to so move the stop; substantially as specified.

4. In a calculating machine having multiple-order accumulator mechanism, including numeral wheels and carrying mechanisms, in combination a canceling device for restoring the accumulator mechanism to normal position or zero; a stop moved with the canceling device; a stop actuating part moved with the canceling device; and a swinging stop movable to engage the stop which moves with the canceling device and having a part which may be engaged by the stop actuating part at the end of the final movement of the canceling device, to operatively position the swinging stop and prevent rebound; substantially as specified.

5. In a calculating machine having multiple-order accumulator mechanism and a series of column-actuators, in combination a canceling device adapted to advance a plurality of the orders from diverse positions to a predetermined limit; cancellation controlling means to operate said canceling device

and effect a succeeding adding movement of the series of column actuators; and a stopping device for engaging the cancellation controlling means, after it has completed the cancellation, and preventing a rebound of the same; substantially as specified.

6. In a calculating machine having multiple order accumulator mechanism and a series of column actuators, in combination a canceling device adapted to advance a plurality of the orders from diverse positions to a predetermined limit; cancellation controlling means to operate said canceling device, comprising a cam, a stop connected with the said cam and turning therewith, a stop on the frame of the machine, and means for moving the second stop into the path of the stop on the cam when the zeroizing operation is completed to hold the cancellation controlling means from rebound; substantially as specified.

Signed by me on the 27 day of March, 50
1913, in the presence of two subscribing witnesses.
